United States Patent Office.

HARRY BITTER, OF PHILADELPHIA, PENNSYLVANIA.

Letters Patent No. 69,896, dated October 15, 1867.

IMPROVEMENT IN COMBINED HOSE, TONGS, CLAMP, WINCH, AND PICK.

The Schedule referred to in these Letters Patent and making part of the same.

TO ALL WHOM IT MAY CONCERN:

Be it known that I, HARRY BITTER, of the city and county of Philadelphia, and State of Pennsylvania, have invented a new and useful Combination of an Elastic Facing-Ring, Coupling-Wrenches, and Detaching Pick with Hose Clamps; and I do hereby declare that the following is a full and exact description thereof, reference being had to the accompanying drawings, and to the letters of reference marked thereon.

The nature of my invention consists in the combination of an elastic facing-ring, coupling-wrenches, and detaching pick with the hose clamp of Patrick H. Collins, dated April 30, 1867. It will be understood by the following description. In the accompanying drawings, which make a part of this specification—

Figure 1 is a reverse plan or view from beneath of the improved device.

Figure 2 is an edge view of the same in its reversed position.

Figure 3 is a face view of the facing-ring D.

Figure 4 is a modification as to the plan of confining the jaws A and A'.

Like letters in all the figures indicate the same parts.

A and A' are concave jaws, which have handles, a and a', that are half lapped together and secured by means of a rivet, b, on which they turn. The jaws, when brought towards each other on the hose, are confined by means of the ratchet B, which is held in place by the spring C. So far the device is substantially the same as that of Patrick H. Collins, above referred to.

The invention consists in the combination of the following devices with the clamp, viz:

D is a ring, of gutta percha, leather, or other similar substance, which I confine to the jaw A, as seen in fig. 2, by means of rivets c, or otherwise. A face view of this ring is seen in fig. 3. This takes the place of the knife-edge projection in Mr. Collins's patent, and is a more effective mode of stopping the leak. The jaw A' may be faced in the same manner, if desired. The device is made to perform the functions of an ordinary spanner by means of the coupling-wrench d in the jaw A' for screwing and unscrewing the Bliss coupling, the wrench e, in the end of the handle a, for operating either the Bliss or Jones coupling, and the pick f, at the termination of the handle a', for detaching the Jones coupling.

When the device is used in place of the ordinary spanner, the handles a and a' are held firmly together by the ratchet B. The jaws A and A' may be held in position without the use of the ratchet B by means of the screw E, in connection with the lugs g g, as represented in fig. 4.

What I claim as my invention, and desire to secure by Letters Patent, is—

The combination of the facing-ring D, wrenches d and e, and pick f with a hose clamp, substantially as described and for the purposes specified.

In testimony whereof I have hereunto set my hand and affixed my seal this third day of August, 1867.

HARRY BITTER. [L. s.]
